IGNITION SYSTEM

Filed Dec. 31, 1928

UNITED STATES PATENT OFFICE

JAMES L. ARTHUR, OF ANDERSON, INDIANA, ASSIGNOR TO DELCO-REMY CORPORATION, OF DAYTON, OHIO, A CORPORATION OF DELAWARE

IGNITION SYSTEM

Application filed December 31, 1928. Serial No. 329,554.

This invention relates to electric switches and particularly to a switch adapted for use in connection with ignition apparatus disclosed in my copending application, Serial No. 198,682 filed June 13, 1927, in which the apparatus comprises an ignition coil having two primary windings which are connected by a suitable switch either in parallel with a storage battery or other current source or 10 in series therewith.

This apparatus can be used advantageously in the electrical system of an automobile in which a storage battery, charged by a generator driven by the automobile engine, is 15 used to supply current during the cranking of the engine to the ignition apparatus, and generally to the starting apparatus where an electric starter is used.

In cases where the battery is partly discharged or the starting apparatus considerably drains the battery, thus reducing its voltage substantially below normal, sufficient ignition coil energy can be obtained for ignition purposes while cranking, if the ignition 20 primary windings are connected in parallel with the battery in order to reduce the total resistance of the ignition primary circuit. Where ignition current is supplied by a generator at normal voltage during the running 25 of the engine, the primary windings should be connected in series in order to increase the resistance of the primary circuit and prevent an abnormal flow of current through the ignition coil while the engine is running.

The usual ignition switch is supplemented by a second switch connected to the coil windings and this supplemental switch has a "start" position in which the primary windings are connected in parallel, and a "run" 30 position in which the windings are connected in series with the battery.

One of the objects of the present invention is to provide an improved switch for controlling the ignition apparatus of the application referred to. More particularly, it is an object to provide a switch operable coincidentally with the actuation of the starting motor switch so that the primary windings may be connected in either "start" or "run" 45 relation; and to provide a switch in which

means are employed for moving the switch from one position to the other position automatically when the starting motor switch is actuated or released. This feature provides for automatically reducing the current 55 in the primary circuit of the ignition system and relieves the operator of the necessity to return the shifting switch to "run" position after the engine becomes self operative, and thereby precludes damage resultant upon the 60 contact points of the ignition system.

Further objects and advantages of the present invention will be apparent from the following description, reference being had to the accompanying drawings, wherein a preferred embodiment of one form of the present 65 invention is clearly shown.

In the drawings:

Fig. 1, is a view in diagrammatic form illustrating the electrical circuit when the 70 coil windings are arranged in the normal or "run" relation.

Fig. 2, is a view similar to Fig. 1, but with the coil windings arranged in "start" relation. 75

With particular reference to the drawings the ignition apparatus with which the present switch is particularly adapted to be used, will first be described. The ignition coil is sectionally divisible and has 80 two primary windings 20 and 21 which are inductively related to a secondary winding 22. Winding 20 is connected by wire 23 with a switch contact 24 and by wire 25 with a terminal 26 which is connected with 85 an ignition timer 27 grounded at 28. The winding 20 is also connected by wire 29 with a switch contact 30. The winding 21 is connected by a wire 31 with a switch contact 32 and by a wire 33 with a contact 34, and also with a terminal 36 by a wire 35. Terminal 36 is connected with a battery 37 grounded at 38, by a wire 39, through the usual ignition switch 40, which connects with the battery 90 lead 41.

The secondary winding 22 is inductively related to the primary windings in any one of the preferred forms, but is here illustrated as being grounded at 45 and connected by 100

lead 46 with the ignition distributor 47, as is well known to those skilled in the art. Operatively associated with the ignition circuit, there is provided a multiple circuit switch 50 interposed between the primary windings 20 and 21, and connected to the contacts or terminals described above, as will presently appear. The multiple circuit switch 50 is coincidentally operable with the alteration of the starting motor circuit through the agency of an electroresponsive device 70, which is energized and deenergized when the starting motor control 80 is actuated to close or open the circuit to the engine cranking means 90.

The switch 50 includes movable contact connectors 51 and 52, and when moved to the position shown in Fig. 2, known as the "start" position of the switch, or the position occupied by it during the cranking of the engine, the primary windings 20 and 21 will be connected in parallel with the battery. The arrows 42 and 42^a designate the direction of current flow so that these parallel circuits may be clearly apparent. After the engine has become self-operative, the switch is automatically moved to the "run" position to move the connectors 51 and 52 into the position shown in Fig. 1. Then the switch 30 connects the primary windings 20 and 21 in series with the battery to increase the resistance of the primary circuit and to reduce the current therein to normal value. The series connection of the windings 20 and 21 is clearly indicated by the arrows 43 in Fig. 1. It will be noted that the connections are so made that the coils 20 and 21 also act cumulatively regardless of how they are connected with the battery.

The battery lead 41 is joined with the wire 39 from the terminal 36 as at 44, which provides a terminal for connection with the starting motor circuit. This starting motor circuit is connected to the electric source 37, in parallel relation to the ignition circuit just described; and includes the lead 41 to the terminal 44. To the post 44 is connected a wire 48 being electrically connected to the terminal of the starting motor switch 80. The circuit is completed by wire 83 from the terminal 82 connected with the starting motor or engine cranking means 90, and thence connected to the ground at 92 by means of the wire 91.

As illustrated in the drawing, the coils 20 and 21 have their associated contacts 24, 30, 32 and 34 arranged in a predetermined fixed relation for cooperation with the contact points of the switch 50, as will soon appear.

The switch for controlling the circuits of the ignition coil and altering the relation of the primaries 20 and 21, is indicated generally at 50, and includes the contact connectors 51 and 52 earlier referred to. The connectors 51 and 52 are carried by the block of in-

sulating material 53, being pivotally supported for oscillation as at 54 and 55. Each of the connectors 51 and 52 are provided with contact points 56, 57, 58 and 59 respectively. The movable contact assembly just described is provided with an actuating member as the shouldered pin 60 mounted upon the block 53.

In addition to the coil contacts 24, 30, 32 and 34 already described, there are provided other contacts associated, therewith, for aiding in the alteration of coil relation. It will be noted upon reference to the drawing, that the coil contacts 24 and 30 are arranged to cooperate with the connector contact 56, while the coil contacts 32 and 34 cooperate with the connector contacts 57 and 59 respectively.

The other contacts referred to, include a contact 61 joined to the coil contact 24 by the element 62, and so associated with the structure as to cooperate with the contact 58. Similarly, a contact 63 is joined to the coil contact 34 by an element 64, for engagement by the connector contact 57. Likewise, the contact 65 is joined by an element 66 to the terminal 36, and thence by the wire 35 to the coil contact 34, and is associated in engageable relation with the connector contact 59. The element 67 indicates a blank, or other means that may operate as a stop or detent for limiting the movement of the movable contact assembly, and for convenience of illustration is shown as cooperating with the connector contact 58.

Means are provided for actuating the supplemental switch or coil changing means from the position illustrated in Fig. 1 to that position illustrated in Fig. 2, and embraces the electro-responsive unit 70. This unit may embody an electro-magnet, an electro-thermal or other similar devices, but for convenience of illustration is here shown as an electro-thermal device.

The unit 70 includes a support 71 to which is fixed a bi-metallic element 72 terminating in a tongue member 73. A helical spring 74 connects the unit 70 with the pin 60 of the multiple circuit switch 50, by having one end thereof disposed about the tongue 73, and the other end about the pin 60. This in effect forms an articulated connection between the elements 50 and 70, and drivingly connects the one to the other. The unit 70 is energized by the thermal circuit 75, tapped off from the starting switch contact 82, and including a coil or heating element 76 disposed about the bi-metallic element 72, and grounded as at 77. From this, and by reference to the drawing it will be seen that the thermal circuit 75 is energized coincidentally with the energization of the engine cranking means 90.

The operation of this device is apparent from the consideration of the drawing, and it is obvious that the actuation of the start-

ing switch 80, will move the switch assembly 50 to change the relation of the primary windings.

In Fig. 1, of the drawings, the primary coils are illustrated in the normal or "run" relation, in which the sections 20 and 21 are serially connected, as by means of the connector 51 engaging with the coil contacts 24 and 32.

When the starting motor circuit is closed by the control 80, the thermal circuit 75 is also energized, which causes the bi-metallic element 72 to function. The thermal circuit 75 when energized, heats up the element 72 causing it to flex from the position shown in Fig. 1, to the position shown in Fig. 2, and in doing so causes the multiple circuit switch 50 to pivot on the members 54 and 55 to assume the position illustrated in Fig. 2, in which the primary sections are connected in the parallel or "start" relation. By reference to Fig. 2 it will be noted that energy from the battery 37 now divides at the terminal 36, and follows two parallel circuits, each through one of the primary sections until they are joined again at the terminal 26. From thence, a common conductor transmits the energy to the ignition timer 27 in the usual manner. As soon as the motor becomes self operative, or as soon as the starter operating member 80 is released the thermal circuit is deenergized and the element 72 is cooled, which permits the unit 70 to retract and to return the contact carrier 53 to the "run" position illustrated in Fig. 1.

Thus, it is seen that provision is made for automatically shifting the switch mechanism 50, from the "run" to the "start" position upon closing of the starting motor circuit, and that means are also provided for automatically changing the relation of the primary sections from "start" to "run" upon release of the starting motor switch, which relieves the operator of the necessity of manually changing the relation of the primary windings, a failure of which would probably result in damage to ignition points or other elements of the system.

While the form of embodiment of the present invention as herein disclosed, constitutes a preferred form, it is to be understood that other forms might be adopted, all coming within the scope of the claims which follow.

What is claimed is as follows:

1. In an electrical system for use with internal combustion engines, the combination, with a source of electrical current and engine starting means energized thereby, of an ignition circuit also energized from said source, and automatic means for decreasing the normal resistance of said ignition circuit coincidentally with the energization of said engine starting means, comprising a sectionally divisible primary coil, and electroresponsive means energizable by said source and oper-

able to change the relation of said primary coil sections.

2. In an electrical system for use with internal combustion engines, the combination, with a source of electric current and engine starting means energized thereby, of an ignition circuit also energized from said source, and automatic means for decreasing the normal resistance of said ignition circuit coincidentally with the energization of said engine starting means, comprising a sectionally divisible primary coil, a multiple circuit switch interposed between the coil sections, and electroresponsive means energizable by said source and operable to change the relation of said primary coil sections by operation of said switch.

3. In an electrical system for use with internal combustion engines, the combination, with a source of electric current and engine starting means energized thereby, of an ignition circuit also energized from said source, and automatic means for decreasing the normal resistance of said ignition circuit coincidentally with the energization of said engine starting means, comprising a sectionally divisible primary coil, and electroresponsive means energizable by said source and operable upon said switch to change the relation of said coil sections.

4. In an electrical system for use with internal combustion engines, the combination, with a source of electric current and engine starting means energized thereby, of an ignition circuit also energized from said source, and automatic means for decreasing the normal resistance of said ignition circuit coincidentally with the energization of said engine starting means, comprising a sectionally divisible coil in said circuit, a multiple circuit switch interposed between said coil sections, and electroresponsive means energizable by said source and operable upon said switch to change the relation of said coil sections.

5. In an electrical system for use with internal combustion engines, the combination, with a source of electric current and engine starting means energized thereby, of an ignition circuit also energized from said source, and automatic means for decreasing the normal resistance of said ignition circuit coincidentally with the energization of said engine starting means, comprising a sectionally divisible coil in said circuit, a multiple circuit switch interposed between said coil sections, and electro-thermal means energizable by said source and operable upon said switch to alter the relation of said coil sections.

6. Ignition apparatus for internal combustion engines comprising, a current source, an ignition circuit including a coil having a plurality of primary windings, a switch for connecting the windings in parallel for engine starting ignition and in series for engine running ignition, and means for operating said

switch coincidentally during the starting operation.

7. Ignition apparatus for internal combustion engines comprising, a current source, 5 an ignition circuit including a coil having a plurality of primary windings, a switch for connecting the windings in parallel for engine starting ignition and in series for engine running ignition, and electro-responsive means operably connected to the switch for automatically changing the relation of the windings during engine starting.

8. Ignition apparatus for internal combustion engines comprising, a current source, 15 an ignition circuit including a coil having a plurality of primary windings, a switch for connecting the windings in parallel for engine starting ignition and in series for engine running ignition, and electro-responsive switch operating means for automatically changing the relation of the primary windings while the engine is being started.

9. Ignition apparatus for internal combustion engines comprising, a current source, an ignition circuit including a coil having a plurality of primary windings, a switch for connecting the windings in parallel for engine starting ignition and in series for engine running ignition and electro-thermal switch 30 operating means for automatically changing the relation of the primary windings while the engine is being started.

10. Ignition apparatus for internal combustion engines comprising, a current source, 35 an ignition circuit including a coil having a plurality of primary windings, means for alternately changing the windings from series relation for engine running ignition to parallel relation for engine starting ignition, and means for coincidentally operating the changing means while the engine is being started.

11. Ignition apparatus for internal combustion engines comprising, a current source, 45 an ignition circuit including a coil having a plurality of primary windings, means for alternately changing the windings from series relation for engine running ignition to parallel relation for engine starting ignition, and 50 electro-thermal means operable upon said changing means for automatically insuring a parallel relation of said windings during engine starting and a series relation of said windings during engine running.

55 12. In an ignition system, the combination of a current source; an ignition circuit including a plurality of primary coils in series with the source; a circuit including a starting motor and switch in series with said source, 60 and in parallel with the ignition circuit; a third circuit including an electro-thermal unit in series with said source and switch and in parallel with said motor and coil; means interposed between the said primaries 65 and operable by the electro-thermal unit

for altering the relation of the coils when said unit is energized and deenergized; and a secondary circuit in inductive relation to the primary circuit.

13. The apparatus defined by claim 12 in 70 which the electro-thermal unit is energized and deenergized coincidentally with the starting motor, and alters the coil relation from series to parallel and parallel to series respectively. 75

14. In a starting and ignition system for gas engines, a motor for revolving the engine shaft at starting, a battery electrically connected to said motor, an ignition coil comprising two primary windings, an interposed multiple circuit switch capable of connecting said windings in either parallel or series relation to take current from said battery, a starting switch for the motor circuit, and a shunt controlled by said starting switch 80 and including an electro-responsive device for actuating the multiple circuit switch to alter the relation of said primary windings. 85

15. The starting and ignition system defined in claim 14 in which, the shunt includes 90 an electro-thermal unit for shifting the multiple circuit switch.

16. The starting and ignition system defined in claim 14 in which, the shunt includes an electro-thermal unit for shifting 95 the multiple circuit switch, to establish the primary winds in parallel relation during starting and in series relation during running ignition.

In testimony whereof I hereto affix my signature. 100
